UNITED STATES PATENT OFFICE

FRED A. BAILEY, OF OMAHA, NEBRASKA

WINDOW VENTILATOR

Application filed September 12, 1929. Serial No. 392,086.

This invention relates to a window ventilator, and has for its object to provide an elongated box adapted to be disposed between the lower sash and window-stool, said box being 5 apertured to permit air to enter and being extensible so that it may have a length equal to to the width of the window sash.

The invention includes an elongated, hollow, apertured, extensible box of angular 10 form in cross-section providing a vertical part which, when exposed to the weather, will exclude rain or snow, and providing a horizontal part which will be housed from the weather for conducting air into a building.

15 The invention also includes an extensible ventilating-box which may be readily placed in operative position or removed and of such construction that when ventilating a room the air which enters will be deflected upwardly, 20 and that a horizontal draft into the room will be avoided. Also the invention includes a pair of holder-lugs for the ends of the box which prevent displacement.

With the foregoing objects in view the invention presents a new and useful construction, combination and arrangement of parts as described herein and claimed, and as illustrated in the accompanying drawing, it being understood that changes may be made 25 in size, proportion and minor details, said changes being within the scope of the invention as claimed.

In the drawing, Fig. 1 is a side view of the device, showing the outer or weather side 30 thereof and Fig. 2 is a top plan view of the same.

Fig. 3 shows the device mounted in operative position, the window sash, stool and sill being in transverse section. Fig. 4 is an end 35 view of one of the boxes of the ventilator. Fig. 5 is a view in transverse section through a ventilating-box. Fig. 6 is a plan view partly in section showing relative position of the ventilator when extended.

40 Referring now to the drawing for a more particular description, the invention is shown and described in connection with the lower sash 10 and stool 11 of a window, the window sill and parting strip being indicated respectively at 12 and 13.

In order that the objects may be attained as first mentioned I provide boxes arranged in pairs, as the box 14 and second box 15, said boxes being hollow and angular in cross-section and each providing a vertical part *a* and 55 horizontal part *b* (Figs. 4, 5) when placed in operative position.

The boxes may be constructed of any suitable material, but sheet metal is preferred, and in order that they may be collapsed or extended when used in pairs, the box 15 is somewhat larger in cross-section so that the box 14 may have sliding movements in said box 15 to be adjusted longitudinally thereof.

60 The inner ends of the boxes are open and the outer end of each box is provided with a holder-lug or projection 16, and when the device is placed in operative position its vertical part *a* may rest upon the window sill 12 with its horizontal part *b* resting on the 65 window stool 11, its projections 16 engaging between the window stops 17 and parting strips 13.

70 The outer or vertical wall *a* of each box is provided with apertures 18 and their upper 75 horizontal walls *b* are provided with apertures 19, and as thus described the apertures 18 will be disposed closely adjacent to the window sill 12 and exposed to the weather, the apertures 19 being disposed inwardly of 80 and adjacent to the lower rail of the window sash within the building, the apertures 18 operating as intake-ports for air, and the air moving upwardly and discharged through the apertures 19.

85 It will thus be seen that while the air may have a free movement into a room, any draft of air will be directed upwardly, and will not move horizontally into a room, this obviously being a desired feature. Also since 90 the apertures 18, at the outside of a building, are disposed in a plane lower than the apertures 19, snow or rain will not enter.

95 In operation, the lower part of the window sash should engage the top surface of the device but will not obstruct the apertures 19 since these apertures 19 are disposed near the inner edge of the horizontal part *b* of each box. Since the sash 10 may be moved upwardly and downwardly incident to its use it 100

is necessary to provide means to prevent displacement of the device, and therefore the holder-lugs 16 are provided as mentioned.

In operation, after the lower window sash has been raised the device is extended so that its holder-lugs 16 at its ends will be disposed between the parting strips 13 and adjacent window-stops 17, the horizontal parts *b* of the boxes resting on the window stool and the vertical parts *a* thereof resting upon the window-sill. The window is then lowered so that it will engage the top of the boxes adjacent to the apertures 19.

Numeral 20 indicates a slot which is formed in the box 15 near its inner end in line with the apertures 18, and at 21 is indicated a slot which is formed in said box 15 near its inner end, said slot being in line with the apertures 19, these slots being for the purpose of permitting a free movement of air through the ventilator and preventing any part of the box 15 from obstructing the apertures of the box 14. It will be understood that the length of the ventilator when extended will be equal to the width of the window sash, and when the ventilator has been adjusted or extended some of the apertures of the box 14 near its inner end, might be obstructed for the reason that the apertures might not be disposed in register with each other. By use of the slots mentioned there will be no obstructions from the causes mentioned.

I claim as my invention,—

35. 1. In a window ventilator for buildings, a hollow elongated box angular in cross-section having aligning apertures in its top and aligning apertures in its side, a second hollow elongated box formed with aligning apertures in its top and aligning apertures in its side and adapted to have sliding movements in the first named box, the top and side of said first named box having slots formed therein in alignment with its apertures.
40. 2. In a window ventilator for buildings, a hollow elongated box angular in cross-section having aligning apertures in its top, aligning apertures in its side and a holder-lug projecting beyond its end, a second hollow elongated box having aligning apertures in its top, aligning apertures in its side and a holder-lug projecting beyond its end and adapted to have sliding movements in the first named box to dispose its holder-lug at selected distances therefrom with its apertures disposed in alignment with the apertures of said first named box, the top and sides of the first named box having slots formed therein in alignment with its apertures.

In testimony whereof, I have affixed my signature.

FRED A. BAILEY.
